(57) **CLAIM**

We claim the ornamental design for a fluffer tooth, substantially as shown and described.

DESCRIPTION

FIG. 1 is a perspective view of a fluffer tooth showing our new design.

FIG. 2 is a top plan view thereof.

FIG. 3 is a side elevation view thereof taken from the right side in FIG. 1.

FIG. 4 is a front elevational view thereof.

FIG. 5 is a rear elevational view thereof; and,
FIG. 6 is a bottom plan view thereof.
